UNITED STATES PATENT OFFICE.

ALBERT PETER THURSTON, OF LONDON, ENGLAND.

STRIP OR SHEET METAL STRUCTURE.

1,421,618.

Specification of Letters Patent.

Patented July 4, 1922.

Application filed January 6, 1920. Serial No. 349,738.

To all whom it may concern:

Be it known that I, ALBERT PETER THURSTON, a subject of the King of Great Britain and Ireland, residing at London, in 5 the county of London, England, have invented new and useful Improved Strip or Sheet Metal Structures, of which the following is a specification.

This invention relates to improved strip 10 or sheet metal structures of substantially I-girder form made from metal strip or sheet which is corrugated longitudinally of the finished members in order to develop the full strength of the metal in compression, so 15 that the thickness of the metal required for the loads to which the members are to be subjected is reduced to a minimum.

The object of the invention is to form 20 such sheet or strip metal structures with closed tubular portions along the edges of each corner where the metal is most effective in resisting compressive stresses.

A further object of the invention is to 25 form these tubular portions as closed tubes and so enable them to carry the maximum load without collapsing.

A still further object of the invention is 30 to connect each closed tubular portion to each of the two adjoining closed tubular portions by one web and one flange, which web and flange are stiffened to withstand shear and longitudinal compression stresses by being bent about longitudinal axes so that the webs and flanges of the structure in addition 35 to connecting the closed tubular portions together may take a considerable proportion of the compressive stresses and so relieve the closed tubular portions of some of the stress.

40 A still further object of the invention is to connect each closed tubular corner member to another closed tubular corner member by a closed tubular flange and to another closed tubular corner member by a 45 corrugated web which is connected midway to an oppositely corrugated web similarly connecting corresponding closed tubular corner members to form the structure as a series of tubes so that in the case of local 50 injury to the structure or a portion being shot away there will still remain sufficient metal left suitably shaped to resist stress and to enable the structure to sustain its load.

Members made according to this invention 55 are consequently very suitable for use in the construction of aeroplanes and other air-

craft, and the invention is chiefly intended for, but not limited to, the construction of aeroplane spars, struts and other parts.

With these and other objects hereinafter 60 set forth the invention consists in the improved structure hereinafter described and claimed.

The invention is illustrated in the accompanying drawings, in which:—

65 Figure 1 shows a cross-section of a structural member constructed according to my invention in which one tube on each flange is integrally formed with one web and another tube on each flange is integrally 70 formed with the other web.

Figure 2 shows a similar view of a modification in which the tubes on one flange are integrally formed with one web and the tubes on the other flange are integrally 75 formed with the other web.

Figure 3 shows a cross sectional elevation 80 of a structural member in which the tubular flanges are formed separately from the webs.

Figure 4 shows a similar view in which the 85 corrugated member interconnecting the tubes on the flanges is formed separately therefrom.

Figure 5 shows a cross sectional elevation 90 of a structural member having three tubular members arranged on each flange.

In Fig. 1, the member consists of two 95 similar components 1 and 2 which are substantially L-shaped in cross section. Considering the cross section, the top and corner 100 of each component are of tubular form as at 3 and 4 while the long arm or web of each L is corrugated in a sinuous curve, consisting of two ends 5 and 6, concave, and a centre 7, convex with respect to the interior 105 of the L. The short arm or flange of each L is also corrugated in a sinuous curve with the centre 8, concave with respect to the interior of the L. The tubes 3 and 4 are somewhat elliptic, their major axes being at 110 right angles to the long arm. The walls of the tubes join the body of the L in gentle curves as shown. Each of the components 1 and 2 of the member thus consists of two tubes integral with a corrugated connecting- 115 web 1 or 2 and a corrugated flange, and may be formed by rolling or pressing a metal strip or sheet. The two components are placed side by side in inverse positions, so that the centres 7, meet at or near the centre 110 line of the finished member shown sectionally in all figures, and the flange of one

component L, as 1 touches a tube of the other component L, as 2. The two components 1 and 2 are then secured together where they touch at 9, by riveting, by eyeleting, or by 5 spot or strip welding. The meeting walls of the tubes are also preferably secured together at 12, by riveting, by eyeleting, or by spot or strip welding.

In Fig. 2 the member is also built up of 10 two L-shaped components 1 and 2; in this construction, both the tubes 3 and 4 of each component are integral with the flange instead of one tube being integral therewith, as in Fig. 1. In this construction, the tubes 15 3 and 4, being integral with the corrugated flange, are connected together thereby across the web.

In Fig. 3, corrugated flanges 13 and 14 formed at their edges with two tubes 3 and 20 4, are connected by a pair of corrugated webs 15 and 16.

In Fig. 4, the tubes 3 and 4, are formed on the webs 15 and 16 and are connected by corrugated flanges 17 and 18.

25 In Fig. 5, each component has two corrugated flanged strips 19 and 20, so as to be substantially of channel, instead of L-cross section, and one flange of each strip is convex, as at 21, while the other is concave as at 22 with regard to the interior of the channel. The flanges of the finished member thus comprise each three tubular parts.

35 In the several structural embodiments illustrated, it will be noted that each completed structure is composed of an even number of parts, either two or four. In the two-part structures, the parts are duplicates, one being reversed for their assembly and 40 the two interfitted. In the four-part structures, each has two pairs of like parts. Thus in the group represented by Figs. 1, 2 and 5, the two complementary elements of the structure are identical and are adopted 45 to interfit when one is reversed relatively to the other and assembled as shown. In Figs. 3 and 4, the top and bottom members are identical and the side members are identical. This duplication affords interchangeability and simplifies and standardizes the construction and assembly.

55 Although several embodiments of my invention have been described by way of example I wish it to be clearly understood that various other modifications may be made without departing from the spirit of my invention or the ambit of the claims.

I claim:

60 1. A strip or sheet metal structure of substantially I-girder section consisting of corrugated webs connected to corrugated flanges and hollow closed tubular portions connected and disposed along the edges of the flanges.

65 2. A strip or sheet metal structure of substantially I-girder section consisting of two

corrugated webs connected together, two corrugated flanges each connected to both webs and a hollow tubular portion at each corner of the structure connected to one web and one flange. 70

3. A strip or sheet metal structure of substantially I-girder section consisting of corrugated webs connected to corrugated flanges and closed tubes connected and disposed along the edges of the flanges. 75

4. A strip or sheet metal structure of substantially I-girder section consisting of two corrugated webs connected together, two corrugated flanges each connected to both webs and tubes at each corner of the structure 80 connected to one web and one flange.

5. A strip or sheet metal structure of substantially I-girder section consisting of two corrugated webs connected on the centre line of the finished structure, two corrugated 85 flanges connected to both webs at opposite sides thereof and closed tubular members formed at each corner of the structure.

6. A strip or sheet metal structure of substantially I-girder section consisting of two 90 corrugated webs connected together, two corrugated flanges each connected to both webs and elliptic tubular portions at each corner of the structure connected to one web and one flange. 95

7. A strip or sheet metal structure of substantially I-girder section consisting of two longitudinally corrugated webs connected together, two longitudinally corrugated flanges each connected to both webs and tubes connected to one web and one flange to form a plurality of thicknesses of metal at each corner. 100

8. A strip or sheet metal structure of substantially I-girder section consisting of corrugated webs connected to corrugated flanges and rolled tubes connected to one web and one flange to form a plurality of thicknesses of metal at each joint. 105

9. A strip or sheet metal structure of substantially I-girder section consisting of two corrugated webs connected together, two corrugated flanges each connected to both webs, and substantially elliptic tubular portions connected to one web and one flange to form 115 three thicknesses of metal at each corner of the structure. 110

10. A strip or sheet metal structure of substantially I-girder section consisting of two longitudinally corrugated webs connected together and two longitudinally corrugated flanges with closed tubes on their edges, said flanges being disposed on opposite edges of 120 said webs and secured thereto.

11. A strip or sheet metal structure of substantially I-girder section consisting of two longitudinally corrugated webs connected together along lines parallel with the axis of the structure two longitudinally corrugated flanges each connected to both webs, and 130

tubular members formed at each corner of the structure and each connected to one web and one flange.

12. A girder substantially of I section comprising two corrugated plates connected together and having their corrugations oppositely directed; said plates forming a web, corrugated flanges connected to the upper and lower ends of the web and closed tubular portions connected to the edges of the flanges.

13. As an article of manufacture a strip or sheet metal structure of substantially I-girder section having longitudinal extending closed hollow portions on the flanges and on the web members.

14. As an article of manufacture a strip or sheet metal structure of substantially I-girder section having longitudinal extending closed hollow portions on the flanges thereof and interconnected by corrugated web members.

15. As an article of manufacture a strip or sheet metal structure of substantially I-girder section having longitudinal extending closed hollow portions of the flanges thereof and interconnected by corrugated web members which are connected together at the centre to form longitudinal extending closed hollow portions on the web member. 25 30

16. As an article of manufacture a strip or sheet metal structure of substantially I-girder section having corrugated flanges connecting together longitudinal extending closed hollow portions of the flanges thereof of interconnected by web members corrugated in a sinuous curve which are connected together at the center to form longitudinal extending closed hollow portions on each web member. 35

ALBERT PETER THURSTON.
